UNITED STATES PATENT OFFICE.

FRANK D. SHULL AND WILLIAM E. SHULL, OF BURNETTSVILLE, INDIANA.

ICE CREEPER.

Application filed October 5, 1925. Serial No. 60,602.

This invention relates to new and useful improvements in ice creepers.

One object of the invention is to provide an ice creeper which is simple in construction, and which can be conveniently and comfortably worn.

Another object is to provide an ice creeper which includes novel ice gripping means movably mounted, and adjustable into and out of ice engaging position.

Another object is to provide an improved means for supporting the ice engaging members, whereby said members are adapted for easy movement into and out of ice engaging position.

Another object is to provide a novel locking means which operates to hold the ice engaging members in either lowered or elevated position.

Other objects and advantages will be apparent from the following description when taken in connection with the accompanying drawing.

In the drawing:

Figure 1 is a side elevation of an ice creeper made in accordance with the present invention, with the ice engaging members in lowered position, broken away.

Figure 2 is a top plan view of the same partly broken away to show the crank shafts.

Figure 3 is an enlarged vertical longitudinal central sectional view on the line 3—3 of Figure 2.

Figure 4 is a vertical transverse sectional view on the line 4—4 of Figure 2, but showing the ice engaging members in raised position.

Referring particularly to the accompanying drawing 10 and 11 represent the upper and lower sole plates of the device, which are held in spaced relation by the connecting posts 12. Apertured plates 13 are secured to and extend between the peripheral edges of the plates 10 and 11, and receive therethrough the shafts 14, which have the cranks 15 on their ends, said cranks being arranged outwardly of the said plates 13. As will be seen from the drawing, there

are two of these shafts 14 across the front portion of the device, and two across the rear or heel portion, and extending around the toe portion of the device is a vertical metal plate or strip 16, which has openings in its side portions receiving the outer ends of the cranks 15. A similar, but shorter

strip 17 is disposed around the heel portion of the device and has openings in its sides to receive the cranks 15 of the rear shafts 14. It will be noted that the cranks stand or extend upwardly, when the creeper members 16 and 17 are in elevated position, and in depressed position when the said creeper members are in lowered position, and that movement of said members longitudinally of the device, and then upwardly or downwardly, will cause said members to change their positions from ice engaging to elevated or non-ice-engaging. When moving the members 16 and 17 into ice engaging position they are manipulated away from each other, that is, the forward one toward the toe of the device, and the rear one toward the heel of the device, and thence downwardly. A reversal of said movements brings the said members into elevated position. To maintain these members 16 and 17 in either elevated or lowered position, a means is disposed between said members whereby to prevent their movement toward or away from each other, said means including link 16' secured to the outer end of the foremost of the cranks of the rear pair, and shown at 18, the forward end of said link being threaded through a sleeve 19 which is carried on a cam lever 20, mounted on the rearmost of the forward cranks. This sleeve 19 is provided with a head 21 which prevents said sleeve from moving rearwardly through the bracket 22, of the cam lever. By rotating said sleeve, in said bracket, the link may be drawn in or let out, as the conditions require. When properly adjusted, and the cam lever is thrown forwardly into horizontal position, the members 16 and 17 may be manually moved either into or out of ice engaging position, and after having moved the members into such position, the operator throws the lever rearwardly and downwardly into horizontal position, thus locking the members against movement. There are two of these cam levers 20, one on each side of the device, and a link 16' connected thereto and with the other end of the foremost of the rear shafts 14. A yoke 23 is connected to the outer ends of the cam levers to permit the operator to operate both of said levers at the same time.

The lower edges of the members 16 and 17 are formed with the serrations 24, to prevent slipping on the ice.

An upwardly extending plate 25 is secured to the rear or heel portion of the upper plate 10, for embracing the heel of the wearer, suitable straps 26 being carried by 5 said plate to be secured about the wearer's foot. Similar straps are attached to the toe portion of the device for engagement over the toe of the wearer's shoe.

Secured to the forward and rearward portions of the lower face of the lower plate 11 are the leather or rubber sole and heel plates 27, whereby to render the use of the device easy when the toothed elements are in elevated position.

15 What is claimed is:

1. An ice creeping shoe comprising a foot plate having depending hangers, transverse shafts supported in the hangers and having terminal crank portions, creeper members 20 disposed for vertical movement with respect to the foot plate and receiving the said crank portions therethrough, and means operatively connected with the said crank portions for rocking the shafts to raise and 25 lower the creeper members.

2. An ice creeping shoe comprising a foot plate having depending hangers at the toe and heel portions, transverse shafts rotatably supported in the hangers and having 30 terminal crank portions, creeper members

vertically movable with respect to the toe and heel portions of said foot plate, and means associated with the crank portions for simultaneously raising and lowering said creeper members.

3. An ice creeping shoe comprising a foot plate having depending hangers, transverse shafts supported in the hangers and having terminal crank portions, creeper members 40 curved in conformity with the toe and heel portions of the foot plate and spaced outwardly therefrom for vertical movement with respect thereto, said creeper members receiving said crank portions therethrough, cam members carried by the crank portions 45 of one of the shafts, links connected to the cam members and to another of the shafts, and means for moving the cam members whereby to produce the rocking of the shafts and the raising and lowering of the creeper members, the connections of the links with the cam members being arranged to move off center in both directions whereby to maintain the creeper members in elevated 50 positions, at times, and in lowered position, 55 at times.

In testimony whereof, we affix our signatures.

FRANK D. SHULL.
WILLIAM E. SHULL.
